UNITED STATES PATENT OFFICE.

ROBERT SCHEANBLUM AND GRACE SCHEANBLUM, OF DANBURY, CONNECTICUT.

COMBINED HAIR FORM AND TIE.

1,413,359.

Specification of Letters Patent. Patented Apr. 18, 1922.

Application filed February 17, 1921. Serial No. 445,808.

To all whom it may concern:

Be it known that we, ROBERT SCHEANBLUM and GRACE SCHEANBLUM, citizens of the United States, residing at Danbury, in 5 the county of Fairfield and State of Connecticut, have invented a certain new and useful Combined Hair Form and Tie, of which the following is a specification.

This invention is a combined hair form 10 and tie adapted to be employed by ladies in arranging their hair in an attractive and æsthetic manner even in the absence of an abundance of hair.

More especially, the invention embodies a 15 device for use in fashioning psyches, swirls, rolls, puffs and similar hair conformations, and is intended especially to operate as a skeleton formation about which the hair may be built up or arranged and suitably secured 20 in any desired conformation.

Hair supports and foundations have been heretofore proposed to accomplish this result generally, but the object of the present 25 invention is to greatly simplify prior constructions, economize in their manufacture, minimize the weight of such devices, facilitate their application, and extend their field of usefulness.

An expedient commonly employed heretofore for the general purposes under consideration consists of a wire base loop, the ends of which are formed into a secondary loop, the latter being adapted to enclose a strand of hair, the loose end of which is adapted 35 to be wrapped about the device to form the puff or roll, and in order that the hair may be built out from the scalp, so as to give sufficient size or bulk to the roll or puff, the intermediate portion of the secondary loop 40 is usually connected with the main loop by bridge wires which form a support therefor and cooperate with the secondary loop and base loop in the formation of a substantially semi-spherical wire framework. A construction 45 of this character not only necessitates the employment of a relatively large amount of wire in its manufacture and the manipulation of such large amount of wire, but in many instances requires more than one 50 length of wire and is unduly heavy and cumbersome for the work intended to be performed thereby.

Furthermore, in devices of this character, wherein a supplemental loop is provided to 55 embrace a strand of hair, it is difficult in the manufacture to form a loop of such a

wide range of adaptability as to enable it to be used for persons having varying amounts of hair. Accordingly, it has been necessary to manufacture several sizes of 60 each expedient in order to meet the varying demands of the users.

The present invention overcomes the disadvantages referred to and others and performs all its functions in a more efficient 65 and expeditious way than the expedients heretofore employed.

From a structural standpoint, the invention, in its preferred form, embodies a base loop adapted to seat on the scalp of the 70 wearer in combination with a wire extending substantially diametrically across the loop and preferably arched longitudinally. The diametrically extending wire divides the loop into two lateral sections or halves, one 75 half of which is preferably closed, the other half being adapted to be open to permit the device to be slipped over a strand of hair without necessarily requiring the hair to be threaded through the loop. In order that 80 the base loop may be thus opened or closed, one end of the same may be conveniently provided with a hook for normally maintaining the loop in closed position.

Features of the invention, other than 85 those specified, will be apparent from the hereinafter detailed description and claims, when read in conjunction with the accompanying drawings.

The accompanying drawings illustrate one 90 practical embodiment of the present invention, but the construction therein shown is to be understood as illustrative, only, and not as defining the limits of the present invention.

Figure 1 is a view of a head showing the manner in which a device embodying the present invention may be applied.

Figure 2 is a perspective view of the device removed; and,

Figure 3 is a plan view of the device.

The device of this invention is preferably formed in one piece from light resilient or spring wire, and, in practice, this wire may be covered with cotton, silk, hair or any 105 other desired material so as to entirely enclose and conceal the wire.

One end of the wire is provided with a hook 1 and the portion of the wire next adjacent the hook is then bent to form a 110 loop 2 being thereafter caused to change direction at 3 and extend substantially dia-

metrically of the loop to form a bridge wire 4, the end of which is curved around the intermediate portion of the loop at 5 to firmly secure it in position.

5 The bridge wire 4 is arched longitudinally and is preferably offset at 6 to form a keeper 7, with which the hook 1 is adapted to engage for the purpose of precluding it from travelling longitudinally of the bridge 10 wire 4 when in position on the head.

It will be understood, however, that while the offset 6 to provide the keeper 7 is preferred, the present invention is not limited in this respect.

15 A device formed in the manner described embodies, generally speaking, a base loop 2, divided by a bridge wire 4 into two lateral halves 8 and 9, the former of which is closed and the latter of which is closed so long as 20 the hook 1 engages with the keeper 7. The lateral half 9 may be opened, however, by disengaging the hook from the keeper and this fact enables the device to be more expeditiously and conveniently applied to hair 25 strands of any size than has heretofore been possible in devices of this character.

In applying the device to the hair, for example in the formation of a psyche, the hair may be gathered at the back of the head into 30 a single strand and while it is thus held in gathered condition, the hook 1 may be disengaged from the keeper and, allowing the lateral half 9 of the base loop to spring out as shown in Figures 2 and 3 enables the device to be slipped in a lateral direction about the strand of hair without requiring the threading of any of the hair through either of the loops 8 and 9. Thereafter and without the exercise of any care whatsoever, the 40 hook 1 may be engaged with the keeper 7 and after this is done, the device may be forced firmly against the scalp while the strand of hair passing through the section 9 is held taut. This operation is made possible by the unusually large area of the loop 45 section 9 which does not cause binding of the hair and permits of ready adjustment of the device on the hair even after in position to encircle the hair strand. In prior devices, 50 the hair, if in abundance, is usually gripped in such manner by the part of the device which surrounds it that adjustment must be made before the device is clamped in position.

55 After the device has been mounted in place on the head, in the manner described, and the hook engaged with the keeper, the hair may be built up on the form in the usual manner and secured in position through the 60 use of hair pins as will be well understood by those familiar with hair dressing.

In the use of the device as described, and as shown in Figure 1, all of the hair to be formed on the device is enclosed within the lateral half 9, yet if the hair dresser so de-

sires, the hair may be separated in two strands or parts and one of these parts passed through the lateral half 8 of the loop and brought together with a strand passed through the lateral half 9 beyond the bridge 70 wire 4. These modes of putting up the hair however are optional with the hair dresser.

In Figure 1 of the drawings, we have shown for illustrative purposes, the manner 75 of employing the device in the building up of hair formations at the top or back of the head. It will be understood, however, that, in practice, the structure is equally well adapted for the making of side puffs or rolls 80 or puffs on any part of the head.

Having thus fully described the invention, what we claim as new and desire to secure by Letters Patent is:

1. A combined hair form and tie embodying a wire bent for a portion of its length to form an open loop the free end of which is provided with a hook, and the remainder of the wire being bent to extend transversely across the loop to the opposite side thereof and there permanently secured to the loop to constitute a distending member which is arched longitudinally.

2. A combined hair form and tie embodying a wire provided at one end with a hook and bent for a portion of its length adjacent the hook to form an open loop, one free end of which loop is provided with the hook, and the remainder of the wire being bent to extend transversely across the loop to the opposite side thereof and there permanently secured to the loop, the transversely extending wire portion being provided adjacent the point of its integral connection with the loop with a fixed keeper adapted 95 to be engaged by the hook to maintain the loop in closed condition.

3. A combined hair form and tie embodying a single wire fashioned into an open loop having a free end provided with an 110 attaching member and the other terminal of the loop having formed integral therewith a bridge member extending substantially diametrically across the loop and secured to an intermediate portion of the 115 loop.

4. A combined hair form and tie embodying a wire bent to form a base loop and also an arched distending element extending transversely of the base loop, one end of 120 the wire being free from permanent attachment to the remainder of the wire except in so far as said end is integral with the wire, and attaching means associated with the free end of the wire for detachably securing said 125 free end to an intermediate portion of the wire.

5. A combined hair form and tie embodying a single wire fashioned into an open loop having one free end shaped to form 130

a hook, and a bridge member extending substantially diametrically of the loop and provided adjacent the loop with an offset portion forming a keeper adapted to cooperate 5 with said hook in order to secure the loop in closed position.

6. A combined hair form and tie embodying a single wire fashioned into an open loop, having a free end provided with a 10 hook shaped member, and the other terminal of which loop forms the starting point of a bridge member extending therefrom sub-

stantially diametrically of the loop and arched longitudinally with its end secured to the loop, said bridge member being provided 15 at its end adjacent the terminal of the loop opposite the hook with an offset portion forming a keeper adapted to be engaged by the hook for securing the loop in closed position. 20

In testimony whereof, we have signed our names to this specification.

ROBERT SCHEANBLUM.
GRACE SCHEANBLUM.
